APPLICATOR FOR HAIR AND SCALP TONICS
OR THE LIKE

Frank H. Merrill, Los Angeles, Calif.

Application July 26, 1937, Serial No. 155,703

5 Claims. (Cl. 132—13)

This invention has to do generally with means for applying tonics or other solutions to scalps or the roots of hair; and is more particularly concerned with applicators of the comb type.

- 5 In order effectively to apply tonics to the hair roots or scalp by the usual "finger tip" method, it is essential that the strands of hair be carefully parted to an extent which will expose the scalp at points where application is to be made.
- 10 This is not only a tedious and unpleasant task, but it is almost impossible to cover the entire scalp with full effectiveness, particularly since the major portion of the tonic is wiped from the fingers by contact with the hair before the scalp
- 15 is reached.

While the more unpleasant features of the above procedure may be avoided by dipping an ordinary comb into tonic and then applying the moist tooth-tips to the scalp by a combing operation, again most of the solution is wiped from the comb long before the scalp is reached and substantially all that remains on the tooth-tips is deposited immediately the scalp is touched, leaving practically none for distribution over the

25 scalp as the comb is subsequently drawn through the hair.

It has been proposed to overcome the above difficulties by the use of so-called "fountain" combs, where the bores of hollow teeth are connected to reservoirs provided in or attached to the body portion of the comb. These arrangements, however, have the common disadvantage of being relatively complicated, unwieldy, and necessarily of such construction that it is difficult

35 to keep the feed-bores clear of scalp accumulations and of tonic which may dry or harden during periods of non-use. Furthermore, the factors entering into the final tonic-delivery from such devices are such that the feed is usually irregular and there is consequently no uniform spread of the correct amount of tonic over the treated portions of the scalp.

Therefore it is among the objects of my invention to provide an applicator which enables one to enjoy all the above mentioned procedures without their accompanying disadvantages. I have provided a device of extremely simple construction and yet one which will deliver tonic, without waste, at the points where that tonic

50 will have full effectiveness. When the comb teeth are drawn over the scalp, the delivery of treating solution is even and free and yet there is no danger of over-delivery or under-delivery at any one point. Further, the applicator is such

55 that, with minimum effort, it may be kept clean,

hygienic and in the best of operating conditions.

Generally, I accomplish the above by the provision of capillary bores or passageways extending longitudinally of the comb teeth from orifices in the tooth tips, the upper ends of said bores being vented to the atmosphere. It is necessary only to dip the tooth tips into a shallow tray of treating solution, whereupon a substantial amount of fluid is drawn by capillary attraction into the bores, where it remains until the comb teeth are passed through the hair and into contact with the scalp. Then, by drawing the comb through the hair with the tooth tips held against the scalp, the solution is drawn from the bores by reason of the wiping contact, and is deposited

5 10 15 over the scalp adjacent the roots of the hair.

Of course, to cover the entire scalp it may be necessary to dip the comb several times, but the filling is accomplished almost instantaneously so this operation can practically be disregarded

20 as a time consumer. Further, I have provided novel means whereby, in spite of the fact that the tooth-cavities are of such size that they are filled by capillary attraction, they are given characteristics which give them relatively large

25 capacity.

Though this is not at all limitative, I find excellent results are obtained by first traversing the scalp with strokes in one direction and then with cross-wise strokes, thus leaving a deposit

30 of what may be considered a net-work of close, crossed lines of fluid which, by reason of the subsequent natural spread of the fluid, will insure that the entire surface of the scalp will receive treatment. And, this is accomplished

35 without waste of fluid, for every bit that is delivered is applied directly to the scalp—none of it is wiped away by the hair—and it is not necessary, as with other devices which depend upon "flooding", to deliver an over-abundance of fluid

40 in order to insure that every portion of the scalp is reached.

Of course, bores of capillary size are prone to become clogged, and in order to avoid the effects

45 of this condition, I preferably make the applicator in halves, the dividing plane being one with the common axial plane of the tooth-bores. Thus, by spreading the halves apart, the half-bores are fully exposed and may be easily wiped

50 or flushed clear of any accumulation.

Other objects and features of the invention will be made apparent from the following detailed description, reference being had to the accompanying drawing in which:

- Fig. 1 is a perspective view of an applicator embodying my invention;
 Fig. 2 is an enlarged section on line 2—2 of Fig. 1;
 5 Fig. 3 is an enlarged section on line 3—3 of Fig. 1;
 Fig. 4 is an elevation showing a variational embodiment of the invention;
 Fig. 5 is a section on line 5—5 of Fig. 4;
 10 Fig. 6 is a perspective view of an applicator having a variational form of registering means between the two halves of the device;
 Figs. 7 and 8 are sections showing variational embodiments of the invention; and
 15 Fig. 9 is a section on line 9—9 of both Fig. 7 and Fig. 8.

In order better to show up the characteristics of the capillary feed bores, the drawing is of an enlarged scale. For instance, the actual applicators here represented by the drawing are about three inches long and about one and one-half inches wide with the individual parts of proportionate size—though, of course, these dimensions are not at all to be considered as limitative on the 25 invention.

Since, in its broader aspects, the invention is not limited to such particularities as the illustrated separable-section feature, I will first describe the applicator without reference to those 30 particularities.

The device is in the general nature of a hair comb stamped, molded or machined from any suitable material such as metal, rubber or composition, and consists of body 10 and depending 35 teeth 11. Extending longitudinally of teeth 11 are capillary bores 12, which open at tips 13 to provide delivery orifices 14. The upper ends 15 of bores 12 extend through body 10 and open to the atmosphere at the upper edge 16 of said body, thus providing vent holes 17 which allow fluid to 40 be drawn by capillary attraction through orifices 14 into bores 12 when tips 13 are dipped into a solution.

Preferably, though not necessarily, bores 12 adjacent tips 13 are of relatively restricted diameter, as shown at 18, the resulting diameter of the orifices being such as will control the delivery of fluid in a manner to insure the deposit of a proper amount thereof when the comb tips are later 45 drawn over the scalp; while the relatively large-diameter portions of the bores (though of capillary size) give sufficient capacity to obviate necessity of too frequent fillings or replenishment.

While the dimensions here given are in no way 50 to be considered as controlling on the invention, I have found that in an applicator of the size represented (which, as has been said, is considerably smaller than the drawing indicates) satisfactory results are obtained with restricted bore portions 55 of about $\frac{1}{32}$ " diameter and upper portions of about $\frac{3}{64}$ " diameter.

Bores of such smaller diameter are obviously 60 prone to become clogged with scalp accumulations or with treating material which may become dried or hardened between periods of use. In the absence of other provisions, it would probably become necessary to clear said bores by running tiny cleaners through the relatively long individual openings, an operation which, at best, would be 65 tedious, unsatisfactory and never fully effective.

To overcome this, I prefer to part the applicator, both body and toothed portions, in a plane 70 which is one with the common axial plane of bores 12, or, in other words, to make the applicator up 75 of two symmetrical half-sections 21 and 22.

Then, when the sections are spread apart, the half-bores carried by each are fully exposed and can be readily and thoroughly cleaned by ordinary washing and brushing operations.

Any suitable releasable means may be employed 5 to hold the sections in the illustrated assembled condition, wherein their corresponding half-bores are in register and wherein all other corresponding parts of the two sections are properly aligned. For instance, I have shown a pair of studs 23 and 10 24 fixed, one each, in sections 21 and 22 and having friction fit in through sockets 25 and 26, respectively, provided in the opposite sections.

To facilitate the spreading of sections 21 and 22, I may provide finger-nail recesses 27 at the ends 15 of the body portions of said sections, as clearly illustrated.

In Figs. 4 and 5 I have shown a variational embodiment wherein all parts similar to those of Figs. 1 to 3 are given the same reference numeral 20 plus the letter "a". Here, however, vents 30 for the upper ends of capillary bores 12a open through transverse passageways 31 to the exposed side face 32 of the body portion of part 22a; instead of to the upper edge of the body portions 25 as described in connection with the showing of Fig. 1.

Fig. 6 illustrates a variational embodiment 30 wherein all parts, except the releasable holding means, are identical with corresponding parts of Fig. 1 and are therefore indicated by corresponding reference numerals plus the letter "b". In this case the releasable holding means comprises a pair of integral side lugs or tongues 33 and 34 extending, one each, from the inner faces of sections 21b and 22b and having snug fit in complementary notches 35' and 36' in the upper edges of the opposite sections.

With the applicator constructed in accordance 40 with the above, it will be seen that all the advantages spoken of in the forepart of this specification may be had. The applicator is filled by merely dipping the teeth into a shallow tray of fluid and that fluid remains in the capillary bores until the teeth have been passed through the hair 45 into contact with the scalp. Then, as the applicator is drawn over the scalp with a combing motion, the fluid is evenly drawn from the capillary bores and deposited directly on the scalp in proper quantity.

Fig. 7 shows a variational embodiment 50 wherein parts similar to corresponding parts of Fig. 1 are given the same reference numeral plus the letter "c". In this case, while bore portion 18c is of capillary size, portion 12c may be of greater 55 than capillary diameter, the capacity of the entire bore thus being greater than in the case of Fig. 1. However, in order that bore 12c may be filled by capillary attraction projections are extended radially into the bore, these projections 60 preferably being in the nature of ribs 35 extending longitudinally of and radially into the bore, the ribs thus breaking the bore up into a plurality of what may be termed capillary passageways 36. The ribs are here shown as being diametrically 65 opposite but stopping short of one another, there being one rib on each section 21c and 22c. When the sections are parted, the defining walls of these 70 passageways are exposed for cleaning.

By such a provision the capacity of the comb 75 may be doubled, for instance, over that of the Fig. 1 type, and yet the advantages of quick-filling by capillary attraction and the final delivery of fluid through an orifice of capillary size are still had.

Fig. 8 shows another variational embodiment wherein the general features and advantages are the same as in Fig. 7. In this figure, parts similar to corresponding parts of Figs. 1 and 7 are given the same reference numeral plus the letter "d".

In this case, instead of the stepped bore of Figs. 1 and 7, bore 12d tapers upwardly and outwardly from orifice 14d, the upper portion of the bore being of greater than capillary size to give increased capacity. Ribs 35d, however, serve to divide the bore up into a plurality of capillary passages, as in the case of Fig. 7, thus allowing the bore to be loaded by capillary attraction. 15 The ribs preferably stop short of orifice 14d, thus leaving bore-portion 18d uninterrupted.

I have found that satisfactory results may be obtained by proportioning the bores and ribs as follows (referring to the form represented by 20 Fig. 8) though this data is given merely by way of example and is in no way to be considered as limitative. Where the length of bore 12d from orifice 14d to edge 16d is 1.5" the orifice may be .046" diameter, the bore tapering up to .062" at 25 vent 17d. Ribs 35d may start .125" from orifice 14d, the sides of each including an angle of 60° and the peaks of the opposed ribs being spaced apart about .02" at a point about .9" from orifice 14d.

30 While I have shown and described preferred embodiments of my invention, it will be understood that various changes in design, structure and arrangement may be made without departing from the spirit and scope of the appended 35 claims.

I claim:

1. An applicator of the character described, embodying a body member and teeth depending from said body member, said teeth having capillary bores extending longitudinally thereof, each 40 of said bores opening at one end to the tip of the associated tooth, and said bores being vented to

the atmosphere at their other ends, the portions of the bores adjacent the tips being of relatively restricted diameter.

2. An applicator of the character described, embodying a body member and teeth depending 5 from said body member, said teeth having capillary bores extending longitudinally therethrough and substantially coextensive therewith, each of said bores opening at one end to the tip of the associated tooth, and said bores being vented 10 to the atmosphere at their other ends; the portions of the bores adjacent the tips being of relatively restricted diameter.

3. An applicator of the character described, embodying a body member and teeth depending 15 from said body member, each of said teeth having a bore extending longitudinally thereof and opening to the tip of the associated tooth, said bore being of relatively restricted diameter where it opens to the tip and having a portion of larger 20 diameter thereabove, and projections extending radially into said portion.

4. An applicator of the character described, embodying a body member and teeth depending 25 from said body member, each of said teeth having a bore extending longitudinally thereof and opening to the tip of the associated tooth, said bore being of relatively restricted diameter where it opens to the tip and having a portion of larger 30 diameter thereabove, and ribs extending longitudinally of and radially into said bore portion.

5. An applicator of the character described, embodying a body member and teeth depending from said body member, each of said teeth having a bore extending longitudinally thereof and 35 opening to the tip of the associated tooth, said bore being of relatively restricted diameter where it opens to the tip and having a portion of larger diameter thereabove, and diametrically opposite ribs extending longitudinally of and radially into 40 said bore portion.

FRANK H. MERRILL.
